CLAIM

The ornamental design for a playing card dealing machine, as shown and described.

DESCRIPTION

FIG. 1 is a perspective view of the playing card dealing machine showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the playing card dealing machine is being used.

The broken lines shown in the drawings represent portions of the playing card dealing machine that form no part of the claimed design.

1 Claim, 9 Drawing Sheets
